(57) **CLAIM**

The ornamental design for an automatic watch winding box, as shown and described.

DESCRIPTION

FIG. 1 is a perspective view of an automatic watch winding box showing my new design;

FIG. 2 is a perspective view from the back thereof;

FIG. 3 is a front elevational view thereof;

FIG. 4 is a rear elevational view thereof;

FIG. 5 is a right side elevational view, a left side elevational view being a mirror image thereof;

FIG. 6 is a top plan view thereof;

FIG. 7 is a bottom plan view thereof; and,

FIG. 8 is a perspective view thereof shown in use.

The broken lines are shown for illustrative purposes only and form no part of claimed design.
